UNITED STATES PATENT OFFICE.

VICTOR A. T. ALBRIGHT, OF BEDFORD, INDIANA.

MOLD.

Application filed January 12, 1926. Serial No. 80,730.

This invention relates to molds and particularly molds used in casting stone-sawing teeth, in the cutting faces of which are embedded such cutting elements as diamonds, 5 diamond chips, carborundum, corundum, sapphires or other suitable abrasive material.

The invention has for its objects improvements in the molds and improvements in the saw-teeth produced in the molds, and is characterized by the provision of means whereby all undue strains resulting from shrinkage are concentrated in parts of the casting that may be removed in finishing the teeth, by the provision of means for facilitating proper positioning of the cutting elements during the casting operation, by the provision of means for permitting the escape of gas during the casting operation, 20 by the provision of means making possible utilization of a major portion of the mold elements in casting different sized teeth, and by the provision of means for insuring proper assembling and positioning of the 25 several elements entering into the mold for a given size of tooth.

Other objects and advantages of the invention will become apparent from the following description when taken in connection 30 with the accompanying drawings in which—

Figure 1 is a side elevation of a mold embodying my invention, a portion thereof being broken away to show the relation of a mold cavity to its gate.

Figure 2 is a view showing, in side elevation, elements of the mold detached one from another, the side pieces being arranged so as to show their inner faces, i. e., the side pieces shown to the left have been turned about so as to show in front their inner faces which fit against the front of the base piece, shown in the middle, and against the inner faces of the rear side pieces, shown to the right.

Figure 3 is an enlarged transverse sectional view, taken on the line 3—3 of Figure 1.

Figure 4 is a view similar to Figure 3 but on a larger scale, showing the middle portion of the mold and the lower portion of a 50 tooth cast within the mold.

Figure 5 is a horizontal sectional view, taken on the line 5—5 of Figure 3 and showing a single mold cavity.

Figure 6 is a top plan view of the mold adjusted to cast a tooth of a given dimension.

Figure 7 is a view similar to Figure 6 showing the mold adjusted to cast a wider tooth.

Figure 8 is a fragmentary side elevation of the parts of the mold, with the upper side pieces slightly separated from the lower side pieces and base piece, and with the upper side pieces adjusted to the relative positions shown in Figure 6, i. e., to produce narrower teeth, and with the proper base piece associated with the lower side pieces to complete the mold and to insure such adjustment of the upper side pieces.

Figure 9 is a view similar to Figure 8 but with the upper side pieces adjusted to the relative positions shown in Figure 7, i. e., to produce wider teeth, and with the proper base piece to complete the mold and to insure such adjustment of the upper side pieces.

Figure 10 is a fragmentary plan view of the lower side pieces associated with a base piece provided with a modified form of venting means.

Figure 11 is a transverse sectional view, 80 taken on the line 11—11 of Figure 10.

Figure 12 is a transverse sectional view, taken on the line 12—12 of Figure 13 and showing another modified form of venting means.

Figure 13 is a fragmentary side elevation of the base piece but with only one of the two lower side pieces associated therewith.

Figure 14 is a plan view of the two lower side pieces associated with a base piece and between which are arranged spacers for spacing the cutting elements from the ends of the mold cavity and over which mold cavity is arranged a screen, partly broken away, for preventing the cutting elements from floating upward when molten metal is introduced into the mold.

Figure 15 is a view in elevation of a locating pin adapted to cooperate with the parts of the mold to insure proper adjustment of the upper side pieces when assembling the mold for different sized teeth.

Referring to the drawings, and particularly to Figures 1 to 9 inclusive, wherein one form of the invention is shown, the mold embodying my invention comprises a base piece 15, upon which are arranged two lower side pieces 16, each carrying an upper side piece 17 and 18, respectively. These five elements when assembled form a plu-

rality of mold cavities 19 and are held together by means of a plurality of horizontally and transversely disposed lag-bolts 20 and 21, and a plurality of vertically disposed tie-bolts 22, the heads of which are adapted to fit loosely within a groove or channel 24 formed longitudinally at the bottom of the base piece 15, and to be held from turning by the walls thereof. This groove or channel not only receives the bolt heads so as to permit the bottom of the base piece to rest flatly upon a table or support and thus permit the assembled mold to stand in an upright position, but it also facilitates the assembling of the mold, since, by reason of the fact that the bolt heads are confined between the side walls of the groove or channel 24, the nuts carried at the upper ends of the bolts may be run down into firm clamping engagement upon the upper side piece without necessitating the application of a wrench or similar tool to the bolt head to prevent its turning.

The lower side members 16 are arranged upon the side ledges 25 of the base piece 15, adjacent to the upwardly projecting tongue 26 thereof, and these lower side members extend an appreciable distance above the tongue 26, as shown. The lag-bolts 21, which pass freely through one of the lower side members 16 and into screw-threaded engagement with the other of the lower side members, also pass through the tongue 26 of the base piece 15, and thereby serve as means for holding the base piece 15 and the lower side pieces 16 in assembled relation preparatory to assembling the upper side pieces 17 and 18. The upper side pieces 17 and 18 are mounted upon the upper faces of the lower side pieces 16 and, as before stated, are clamped thereupon by means of the vertically arranged tie-bolts 22, the upper side pieces 17 and 18 being clamped together by means of the transversely disposed lag-bolts 20, which are passed through elongated openings 27 formed in the upper side piece 17 and into screw-threaded openings 28 of the upper side piece 18. Extensions or protuberances 29 on the inner face of the upper side piece 17, are adapted to fit into the space afforded between the upper and lower flanges 30 and 31, formed on the upper side piece 18, and function cooperatively with the flanges 30 and 31, not only as a means for maintaining the upper side pieces 17 and 18 properly spaced but also as guide means for facilitating longitudinal adjustment of one upper side piece with respect to the other to vary the width of the mold cavities 19. The longitudinal adjustment of one upper side piece with respect to the other is made possible by reason of the elongation of the openings 27 in the upper side pieces 17 through which the lag-bolts 20 project.

The upper side pieces 17 and 18 form the side walls of the several mold cavities 19, and the end walls of these cavities are formed by a plurality of abutments or separators 32 and 32', secured respectively to the upper side pieces 17 and 18 by suitable means, such as screws 33. The upper ends of the abutments or separators 32 and 32' project an appreciable distance above the upper surfaces of the upper side pieces 17 and 18 and the lower ends of these abutments or separators project an appreciable distance below the lower faces of the upper side pieces and into the space afforded between the two lower side pieces 16, which space is somewhat greater than the space afforded between the upper side pieces 17 and 18, and the lower ends of the abutments or separators 32 are thickened to fill this space and shaped so as to present inclined faces 34 which conform with the beveled faces 35 formed at the bottoms of the upper side pieces 17 and 18.

The tongue 26 of the base piece 15 is cut away or relieved at each side directly beneath each mold cavity 19, thus providing slightly inclined walls 36 which form venting or relief passages 37 with the inner faces of the two lower side pieces 16, through which passages gas may escape from the mold cavities 19 to the atmosphere, the escape being made possible by reason of the provision of a plurality of V-shaped ducts 38 formed on the inner faces of the lower side pieces and communicating with vents or ports 39 formed in and extending through the lower side pieces. It will also be noted that the tongue 26 of the base piece is cut away to provide a plurality of depressions 40, each of which is equal in length to the length of the mold cavity. The cutting away of or relieving the tongue 26 to form the slightly inclined walls 36 and the forming of the depressions 40 in the tongue 26 results in the formation of a plurality of webs 41 along the length of the tongue, and the upper surfaces of these webs form the bottoms of the several mold cavities 19. The upper surfaces of these webs are so shaped as to provide a pair of inclined faces 42 lying in planes of approximately 12° to a horizontal plane which intersect each other on a line lying in a central longitudinal plane passing vertically through the several mold cavities. These inclined faces are provided so that the cutting elements, when placed within the mold cavities along the bottom margin thereof, normally tend to lie against the inner faces of the lower side pieces 16; and they are also provided so as to direct the molten metal, when introduced into the mold cavities, outwardly from the center line of the cavities towards the inner faces of the lower side pieces 16. By so directing the molten

metal its flow is utilized to further urge the cutting element 43 to the outer margins of the mold cavities and to maintain them so positioned until the metal has sufficiently hardened to prevent their displacement. In order that the molten metal may be permitted to flow completely around the cutting elements 43 and may thus insure that they will be effectively embedded in the metal of the teeth and held firmly in their proper positions in the cutting faces of the finished teeth, the webs 41 are cut away or relieved adjacent the inclined walls 36 to provide marginal inclined faces 44 at an angle of about 45° to a horizontal plane. Molten metal that enters the space afforded between the inclined faces 44 and the inner faces of the lower side pieces 16, and such slight amount of molten metal as may enter the upper part of the venting passages 37, result in the formation of spurs or fins 45, which may be removed to the extent desired in producing the finished article but will leave the cutting elements surrounded by metal.

In order to retain the cutting elements against their tendency to float upward when the molten metal is introduced into the mold cavities 19, a retaining element 46 is provided, in the form of a wire gauze or screen. This retaining element is sufficient in width to reach from the inner face of one of the lower side pieces to the inner face of the other lower side piece and is sufficient in length to overlie the margins of the tongue 26 adjacent the several webs 41, the overlying end portions of the retaining element being clamped against the tongue 26 by the lower ends of the abutments or separators 32 and 32', which project into the space afforded between the lower side pieces 16. The metal from which the gauze or screen 46 is formed may be such that it fuses with the molten metal as it is introduced into the several mold cavities and thus becomes an integral part of the finished saw teeth.

The upper side pieces 17 and 18 at their upper portions are cut away or relieved, as shown at 47, to provide gates or passages through which the molten metal is poured into the several mold cavities 19, the walls of the gates being so shaped and inclined as to merge with the inner faces of the upper side piece at each mold cavity and thus to permit the metal within the cavities to shrink when cooling without setting up any undue stresses or strains within the body of the teeth. The side piece 17 is further relieved or cut away at an angle adjacent the gates so as to provide overflow channels 48 (see particularly Figure 3), the bottom walls of which form a plurality of cracking edges 49 with the wall of the gates, such cracking edges being located somewhat be-

low the upper faces of the upper side pieces 17 and 18. By reason of the fact that the cracking edges 49 are located below the upper faces of the upper side members 17 and 18 and since the abutments or separators 32 project an appreciable distance above the upper faces of the side members, any overflow or excess metal at the end of the pouring operation (and to insure the filling of the mold an excess is usually poured) is necessarily directed to the overflow channels 48, and, in solidifying, is cracked or broken loose at its point of union with the cast metal by reason of the shrinkage of the metal within the mold, which shrinkage exerts a downward pull against the cracking edges 49 so as to crack or break the overhanging tongue of overflow metal without setting up any undue stresses or strains within the metal in the mold. This tongue and the metal at the gate are usually removed in finishing the tooth and thus all parts of the casting that have been subjected to undue strain during the casting operation are removed in the production of the finished tooth.

The upper side piece 17 is provided at its lower edge with notches 50 and 51 and the upper side piece 18 is provided at its lower edge with notches 52 and 53. Each of the lower side pieces 16 is provided at its upper edge with notches 54 and 55. When it is desired to so adjust the abutments or separators 32, 32', as to mold teeth of say seven-eighths of an inch in width, the two upper side pieces 17 and 18 are so adjusted, when in a face to face relation with each other, as to bring the notches 51 and 53 into alignment or registration with each other, as shown in Figures 1, 6 and 8. A base piece 15, marked "7/8 inch," as shown in Figure 8, is assembled with the lower side pieces 16 and is locked thereto by means of the transverse lag-bolts 21. This base piece 15 is provided with a single notch 56, which registers with the aligned notches 55 of the lower side pieces so that a pin 56' (see Figs. 1 and 15) may be passed through these notches 55, 56, and the notches 51 and 53, when the latter are in alignment, and this is only true when the relative positions of the upper side pieces 17 and 18 are such as to form mold cavities for seven-eighths inch teeth. The base piece 15 marked "7/8 inch" has no other notch than the notch 56, and therefore has a solid portion 57, as shown in Figure 8, which obstructs the passage of the pin through the notches 54 of the lower side pieces 16, and therefore prevents the pin from being passed through these notches. It is therefore apparent that, when the base piece 15, marked "7/8 inch," is assembled with the lower side pieces 16, the assembled parts can be adjusted only to produce a tooth seven-

eighths of an inch wide. Further the base piece marked "7/8 inch" has depressions 40 and webs 41 properly dimensioned for seven-eighths inch mold cavities, so that 5 the mold cavities are in all respects adapted to cast seven-eighths inch teeth.

When it is desired to adjust the parts of the mold for molding teeth say one inch wide, another base piece 15' marked "1 10 inch" (see Fig. 9), is assembled with the lower side pieces 16 in place of the base piece 15. This base piece 15' has a single notch 56", which is in alinement with the notches 54 of the lower side pieces 16 and therefore 15 has a solid portion 58, as shown in Figure 9, which projects across the passageway formed by the notches 55 of the lower side pieces and prevents the pin 56' from being passed through these notches 55. The 20 pin, therefore, can only function by insertion through the notches 54 and this only if the upper side piece 18 has been so adjusted as to bring the notches 50 and 52 into alinement, as shown in Figure 9. This base piece 25 marked "1 inch" has depressions 40 and webs 41 properly dimensioned for one inch mold cavities, so that the mold cavities are in all respects adapted to cast one inch teeth.

While I have shown only two base pieces 30 15 and 15', for insuring two adjustments of the upper side piece 18, it will be understood that other base pieces may be provided which are so notched and are provided with depressions and webs of such dimensions as 35 to enable other relative adjustments to be made of the upper side members, which will also be suitably notched for the different adjustments.

Not only is accuracy made possible by the 40 structure above described, but speed is also made possible in assembling the molds and mistakes are avoided, as will be readily appreciated.

Referring to Figures 10 and 11, wherein 45 is shown a modified form of venting means, the tongue 26' of the base piece 15" is not relieved or recessed at its sides for the escape of gas but is provided with a plurality of relief passages or vents 59, which 50 extend vertically throughout the tongue and establish communication between the mold cavities 19 and the groove 24' formed in the base piece 15".

Referring to Figures 12 and 13, wherein 55 another form of venting means is shown, the two lower side pieces 16' are provided longitudinally of their lengths with grooves or channels 60, which extend throughout the length of the mold. These grooves or 60 channels 60 communicate with the several mold cavities 19 through the relief passages 37 such as heretofore described formed intermediate the tongue 26 and the side members 16', and serve to permit the gases within the mold cavities 19 to escape from the mold at

opposite ends thereof. The base piece 15 is of the same construction as shown in Figures 1 to 5, and as heretofore described.

In order to maintain the cutting elements 43 properly spaced from the ends of the 70 mold cavities so that the teeth when removed from the mold may be milled or otherwise finished at their ends without detriment to the cutting elements, a pair of yoke-shaped spacers 61 may be provided, as 75 shown in Fig. 14. These spacers are adapted to be arranged within the several mold cavities 19 below the screens 46, with their legs in contact with the abutments or separators 32, 32'.

It will be noted from the contour of the mold cavities herein shown that the teeth produced are each provided with a head 62 into the cutting faces of which are embedded the cutting elements 43. These heads are 85 somewhat wider than the main body portions 63 of the teeth so as to provide a clearance between the main portion of the teeth and the material being sawed, to reduce friction and facilitate ease in operation.

Having thus described certain embodiments of the invention what is claimed is:

1. In a mold for saw teeth, side pieces, one of said side pieces being recessed at its top to provide an overflow channel presenting a cracking edge and both of said side pieces forming side walls for the mold cavity, said cavity being enlarged at its bottom, whereby molten metal upon cooling and shrinking within such cavity is so held as to effect a cracking of solidified metal by said cracking edge.

2. In a mold for saw teeth, side pieces forming side walls for the mold cavity, one of said side pieces being recessed at its top to provide an overflow channel presenting a cracking edge and both of said side pieces being relieved at their upper ends to form an inlet gate having inwardly converging walls which are only slightly inclined with respect to said side walls so as to permit unrestricted downward shrinkage of the molten metal upon cooling, said cavity being enlarged at its bottom whereby molten metal upon cooling and shrinking within such cavity is so held as to effect a cracking of solidified metal by said cracking edge.

3. In a mold for saw teeth, a pair of upper side pieces forming the side walls of a mold cavity, a pair of lower side pieces upon which said upper side pieces are arranged, means forming the end walls of the mold cavity, a base piece associated with said lower side pieces and having a tongue forming the bottom of the mold cavity, said tongue being cut away to provide a relief passage and said side pieces being provided with gas ducts communicating with said passages to permit the escape of gas from the mold.

4. In a mold for saw teeth, a pair of separators, a pair of laterally adjustable side pieces, each of which is secured to one of said separators, said separators and said side pieces forming a mold cavity the volume of which may be varied upon adjustment of said side pieces, a base piece forming the bottom of said mold cavity, and means adapted to cooperate with said base piece and said side pieces for insuring a predetermined adjustment of said side pieces.
5. In a mold, the combination with a pair of separators, a pair of laterally adjustable side pieces, each of which is secured to one of said separators, said separators and said side pieces forming a mold cavity the capacity of which may be varied upon adjustment of said side pieces, a plurality of base pieces either of which is adapted to be associated with said side pieces to form the bottom of said mold cavity, and selective means adapted to cooperate with said side pieces and one of said base pieces to insure a given adjustment of said side pieces, said selective means being adapted also to cooperate with said side pieces and another of said base pieces to insure another given adjustment of said side piece.
6. In a mold for saw teeth, a pair of side pieces, a base piece having a tongue arranged intermediate said side pieces and forming the bottom of the mold, said tongue being provided with inclined faces adapted to receive and support thereupon cutting elements to be embedded in the molten metal as it is introduced into the mold.
7. In a mold for saw teeth, a pair of side pieces, a base piece having a tongue arranged intermediate said side pieces and forming the bottom of the mold, said tongue being provided with inclined faces meeting each other centrally of the mold and adapted to receive thereupon cutting elements to be embedded in the molten metal as it is introduced into the mold.

In testimony whereof, I have affixed my signature to this specification.

VICTOR A. T. ALBRIGHT.
